UNITED STATES PATENT OFFICE.

ADOLPH M. HOLSTEIN, OF SYRACUSE, NEW YORK.

DESIGN FOR A BORDER ORNAMENT FOR FURNITURE, CASKET, INTERIOR OR EXTERIOR DECORATION.

52,164.

Specification for Design.

Patented July 9, 1918.

Application filed May 2, 1917. Serial No. 166,046. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Border Ornament for Furniture, Casket, Interior or Exterior Decoration, of which the following is a specification, reference being had to the accompanying drawing, forming a part hereof.

The drawing is an elevation or face view of my design for border ornament.

The design consists of a twisted serpentine band interwoven with conventional

leaves arranged in serpentine form and having small flowers and buds entwined therein, the leaves being in the form of symmetrical curves opposite to the curves of the band and intersecting the band at intervals.

I claim:

The ornamental design for a border ornament for furniture, casket, interior or exterior decoration, substantially as shown and described.

In testimony whereof, I have hereunto signed my name, at Syracuse, in the county of Onondaga, and State of New York, this 27th day of April, 1917.

ADOLPH M. HOLSTEIN.
